Primary Examiner—Celia Murphy*Attorney, Agent, or Firm*—Dennis T. Griggs[57] CLAIM

The ornamental design for a dining bib, as shown and described.

DESCRIPTION

FIG. 1 is a top plan view of a dining bib showing my new design;

FIG. 2 is a bottom plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a perspective view thereof; and,

FIG. 8 is a perspective view thereof, with the dashed lines showing the outline of a person wearing the dining bib for illustrative purposes only and forming no part of the claimed design.
